Primary Examiner — Holly H Baynham*(74) Attorney, Agent, or Firm* — Michael Best & Friedrich LLP(57) **CLAIM**

I claim the ornamental design for a vertical trifold cell phone wallet, as shown and described.

DESCRIPTION

FIG. 1 is a perspective view of a vertical trifold cell phone wallet in a stand configuration according to one embodiment;

FIG. 2 is a right side view thereof;

FIG. 3 is a perspective view of the vertical trifold cell phone wallet of FIG. 1 in an open condition;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines are included for the purpose of illustrating environmental structure and form no part of the claimed design.
